UNITED STATES PATENT OFFICE.

JOHN ASHWORTH AND FRED N. ASHWORTH, OF SOMERVILLE, MASSACHUSETTS.

COVERED ELASTIC BAND.

SPECIFICATION forming part of Letters Patent No. 754,959, dated March 22, 1904.

Application filed September 28, 1903. Serial No. 174,852. (No model.)

To all whom it may concern:

Be it known that we, JOHN ASHWORTH and FRED N. ASHWORTH, citizens of the United States, residing at Somerville, in the county of 5 Middlesex and State of Massachusetts, have invented new and useful Improvements in Covered Elastic Bands, of which the following is a specification.

This invention relates to an improved covering for elastic bands, being used in sleeve-bands, suspenders, and the like, the object of the invention being to produce an elastic band provided with a soft fibrous covering, which is so attached to the elastic band that it will 10 not slip longitudinally thereof and yet will readily yield as the band is stretched and will present a soft exterior surface, which surface at the same time surrounds the elastic band.

The invention consists of an elastic band in combination with a covering therefor, said covering consisting of a series of fibrous strands extending longitudinally of said elastic band and a helical retaining-strand wound around said longitudinal strands under tension, 15 each of said longitudinal strands forming a series of loops extending longitudinally of said elastic band.

The invention further consists in the combination and arrangement of parts set forth in 20 the following specification and particularly pointed out in the claims thereof.

Referring to the drawings, Figure 1 is a side elevation of a portion of an elastic band constructed in accordance with our invention, the elastic band being shown released from tension. Fig. 2 is a side elevation of a portion of an elastic band constructed in accordance with our invention, showing the same with the band stretched and the elastic under 25 tension. Fig. 3 is a longitudinal section taken on line 3 3 of Fig. 1.

Like numerals refer to like parts throughout the several views of the drawings.

In the drawings, 5 is an elastic band of any 30 desirable construction.

6 are strands of fibrous material—such as cotton, wool, or the like—extending longitudinally of the elastic band 5, and 7 is a strand of fibrous material wound under tension

around the elastic band 5 and the fibrous 50 strands 6, said tension being sufficient to hold the fibrous strands 6 against slipping upon the elastic band 5.

In Fig. 2 the elastic band 5 is shown under tension and in the condition in which the 55 same appears when the covering is attached to the band.

The method of manufacturing the band and fibrous material is made the subject of a separate application filed by us of even date here-with, Serial No. 174,851. Said method of manufacturing our improved covered elastic band is in general to stretch the elastic band between two pairs of feed-rolls and while it is stretched to lay strands of fibrous material 60 around the periphery of the band longitudinally thereof and finally to securely bind said bands of fibrous material to the elastic band by means of a cord or fibrous strand wound around said band and strands in a helical path. When the tension on the band 5 is released, the same will contract, as shown in Figs. 1 and 3, and each of the fibrous strands 6 will form a series of loops 8, extending longitudinally of said elastic band, so that between each of the successive convolutions of 65 said helical strand 7 there will be a series of loops extending entirely around the periphery of the band 5 and making in the finished article a covering which is firmly attached to the 70 elastic band 5 and presents a soft, yielding, and pliable surface. If desired, the loops 8 may be of different colors and also instead of being laid straight lengthwise of the elastic band may be laid in a curved or helical path, 75 and thus a large variety of styles and patterns may be obtained to suit the varying requirements of the trade.

Having thus described our invention, what we claim, and desire by Letters Patent to secure, is—

1. As an article of manufacture, an elastic band in combination with a covering therefor, said covering consisting of a series of fibrous strands extending longitudinally of said elastic band and a helical retaining-strand wound around said longitudinal strands under tension, each of said longitudinal strands form-

ing a series of loops extending longitudinally of said elastic band.

2. As an article of manufacture, an elastic band in combination with a covering therefor, 5 said covering consisting of a series of fibrous strands extending longitudinally of said elastic band and a helical retaining-strand wound around said longitudinal strands under tension, said longitudinal strands each forming a 10 series of loops, one loop of each of said series

located between each of the successive convolutions, respectively, of said helical strand.

In testimony whereof we have hereunto set our hands in presence of two subscribing witnesses.

JOHN ASHWORTH.
FRED N. ASHWORTH.
